UNITED STATES PATENT OFFICE.

JOHN V. McMANIS, OF DAYTON, OHIO.

OPERATING-TABLE.

1,286,184.

Specification of Letters Patent. Patented Nov. 26, 1918.

Application filed September 23, 1914. Serial No. 863,086.

To all whom it may concern:

Be it known that I, JOHN V. McMANIS, a citizen of the United States, residing at Dayton, in the county of Montgomery and 5 State of Ohio, have invented certain new and useful Improvements in Operating-Tables, of which the following is a specification.

The invention relates to operating tables 10 to be used in giving movement cure treatments by osteopathic practitioners or for use by surgeons and others. The primary object of the invention is to provide in a table of the described character certain structural 15 improvements hereinafter shown and described and particularly pointed out in the claims.

In the drawings which form a part of the specification—

20 Fig. 1 is a side elevation view of the complete table, and

Fig. 2 is a top plan view of the same with portions of the under supporting structure shown in dotted lines.

25 Fig. 3 is a top plan view of the devices for supporting and adjusting the main table top, the outline of the main top portion being shown in dotted lines.

Fig. 4 is a section on line 4—4 Fig. 3.

30 Fig. 5 is a section on line 5—5 Fig. 3.

Fig. 6 is a sectional view on broken line 6—6 of Fig. 1.

35 Fig. 7 is a top plan view of the supporting devices immediately beneath the middle or drop leaf of the table top.

Fig. 8 is a detail sectional view through the drop leaf adjusting device being taken on line 8—8 Fig. 7.

40 Fig. 9 is a detail sectional view taken approximately on line 9—9 Fig. 6, through the devices for controlling the auxiliary or swinging table section.

Fig. 10 is a detail section of a part of the devices of Fig. 9.

45 Fig. 11 is a sectional view transversely through the main table top approximately on line 11—11 of Fig. 7, with a portion of the top supporting structure being shown in section to disclose the construction thereof.

50 Fig. 12 is a longitudinal sectional view approximately on line 12—12 of Fig. 11, the view also showing a portion of the supporting structure in section.

55 In a treating or operating table of the class to which my invention belongs, it is

desirable that the structure permit of a multiplicity of adjustments and movements securing ease of manipulation for curing and treating physical irregularities of the spine and other bony portions of the human body. 60

In the embodiment of the invention shown in the drawings, the preferable form of supporting means for the table top is a pedestal (see Fig. 1) having a rigid extended base portion indicated by the reference character 10 and an upright portion which may be in the form of a cylinder as indicated by reference character 11. The portion 11 of the pedestal preferably takes the form of a cylinder for receiving a piston or plunger 70 on the co-operating member 12 supporting on its upper extremity the table top. An adjustable connection between member 12 and the portion 11 of the pedestal is preferably provided in the form of a hydraulic 75 lifting means of any desired or common construction not herein shown with the exception of operating lever 13 pivoted to the member 12^a at 14 (see Fig. 11) and having a pivotal connection at 15 with a member 16 comprising a portion of the hydraulic mechanism. 17 is a screw threaded locking member supported in the threaded extension 11^a which is adapted to cause the shoe 18 to be forced against the supporting standard or plunger 12, either to lock the same in an adjusted position or to exert a braking effect on the plunger. An irregularly formed member 12^a is rigidly secured to the upper extremity of the standard or plunger 90 12 and has a depending branch 12^b in the form of an elongated hollow bearing member which serves to pivotally support a portion of the table top as hereinafter described. On the opposite extremity of member 12^a 95 or at an angle of 180 degrees from the projection 12^b is a radial projection 12^c to which the parallel supporting rods 19 and 20 are secured by suitable bolts or machine screws as indicated at 21. The rods 19 and 20 thus 100 rigidly secured to the extension 12^c of the standard 12 are designed to furnish a support for the main table top section which is indicated generally by the reference character 22. In a table designed to manipulate 105 various portions of the frame of the human body as practised by the osteopathic profession I have found that it is a decided advantage to be able to give the main table top section two distinct movements in addition 110

110

to the raising and lowering thereof in vertical planes. These movements are, first, a rocking or canting movement preferably on the longitudinal axis of the table, and second, a longitudinal movement of the main table top on a horizontal plane toward or away from the other two sections of the table top. The small middle section which I mount intermediate the main top sections, 5 is designated by the reference character 23, and the section which I call the auxiliary table section, is designated by the reference character 24 (see Figs. 1 and 2). When the main table section 22 is moved so as to 10 separate or move away from the intermediate sections 23 and 24 of the table top, if the body of the patient be secured by straps or other suitable means to the relative portions it will be seen that by such separation 15 20 a stretching action of the body and frame of the patient may be secured, and hence the longitudinal movement of the main table section is hereinafter referred to as the stretching movement of this section of the table top. This stretching movement as well 25 as the canting or rocking movement of the main table section referred to is provided for by the connection with the supporting members 19 and 20 which is as follows:

30 Mounted on the parallel rods 19 and 20 carried by the pedestal are three triangular shaped supporting brackets designated by the reference characters 25, 26 and 27. The shape of these brackets is best shown 35 by reference to views shown in Figs. 4 and 5 from which it will be seen that each of the brackets is mounted upon rods 19 and 20 of the frame near the outer extremities of the brackets while at the vertex of these brackets 40 openings are made for passing therethrough the adjusting rod 28 which has a crank at its outer extremity as indicated by 28^a, and passing through a bearing member 29 secured to the under side of the main table section. To prevent endwise movement of 45 the threaded adjusting and operating rod 28, in relation to main table section 22, collars as indicated at 30 are secured to the rod 28 on each side of the bearing block 29 (see 50 Figs. 1 to 3 inclusive and Fig. 11). The rod 28 is further supported on the main table section 22 by the bearing members 31 and 32 secured to the main table top. In order to enable the main table top 22 to be adjusted 55 by the manipulation of rod 28, the rod is threaded for a portion of its length, and the supporting member 25 is screw threaded to coöperate with the rod 28 and is fixedly secured to the parallel rods 19 and 20 of the 60 supporting frame by means of set screws as indicated by 25^a, Fig. 1 or other suitable means. The triangular bracket 26 supports the rod 28 and is provided with a set screw 26^a bearing against the shoe 26^b which is in 65 contact with the rod 28 (see Fig. 5). Ad-

justment of the set screw 26^a may be resorted to to bind the shoe 26^b in contact with the adjusting rod 28, to secure it in its adjusted position when desired, or by a slight adjustment of this device any desired kind of 70 breaking effect of the screw threaded rod 28 may be secured. The bracket 27 may be supported on the rods 19 and 20 and on the adjusting shaft 28, while the end of the shaft 28 remote from the crank portion 28^a finds a 75 bearing in bracket 32 which is secured to the underside of the main table section 22. From the construction described it will be seen that a stretching movement may be imparted to the main table section by manipulating 80 the crank 28^a of the rod 28 in the proper direction by which the threaded portion of the rod passing through relatively stationary bracket 25 will operatively engage and shift it, while the rotation in the reverse 85 direction of the threaded rod 28 will restore the main table section to the normal position. With respect to the canting or rockng motion of the main table section 22, it will be seen that this section is supported on an axis 90 consisting of the rod 28 which will permit the main table section 22, in the absence of other supporting means, to rock from side to side until portions thereof contact with the supporting brackets 25, 26 and 27, which 95 are given a pointed shape to permit of this rocking or canting movement. Provision is made for rigidly securing the main table section 22 on its longitudinal axis and this consists of a pivoted lever 35 (see Figs. 1, 2, 100 3 and 5). The lever 35 is provided with a branch U shaped depending member 36 which normally rests in a position to pass by the bracket 26, as the main table top 22 is rocked or canted. The pivotal connection 105 at 35^a however will permit the lever 35 to be moved to a position where the depending members 36 will rest upon the top of the triangular shaped bracket 26 in the manner shown more clearly in Fig. 5, for locking the 110 table top 22 against any canting or rocking movement on the axis rod 28.

One of the important features of my invention resides in the construction of the auxiliary table section and the means by 115 which it is supported in resilient suspension from the table top supporting means 12 through the depending branch 12^b heretofore referred to, which is provided with journal bearings to support the upright 120 shaft 40 (see Figs. 1, 2, 3, 6, 7, 11 and 12). The shaft or spindle 40 is provided with any suitable means as collar 41 by which it is rotatably supported in the bracket 12^b against a downward movement beyond a 125 predetermined limit. Rigidly secured to the upper extremity of the shaft 40 is an irregular shaped bracket 42 extending crosswise of the table top and being provided with ears as indicated by 42^a (see Fig. 7) adapted to 130

take the hinge pins 43 which pass through ears or hinged members 44 secured to the underside of the auxiliary table section 24. Rigidly secured to the lower extremity of 5 the shaft 40 is a block 44^a to which is pivotally secured two parallel arms 45, 46 (see Figs. 1, 2, 6 and 9). The members 45 and 46 extend approximately parallel to the auxiliary table section 24 as will be seen from 10 Fig. 1, and the connection between the outer extremities of these members and the auxiliary table section is secured through a link pivoted at one extremity to the members at 47 and at its other extremity to the under- 15 side of the table top at 48, the latter being a pivot pin passing through a suitable opening in the upper end of the link and the ears of a bracket 49 secured to the underside of the auxiliary table section 24. The link 20 last referred to (see Fig. 10) is a composite member for purposes of adjustment and is preferably comprised of the screw threaded rod 50 which co-operates with an internally threaded tubular member 51. 52 is a threaded locking member for securing the rod 50 in adjusted relation to the tubular member 51. The tubular member 51 is surrounded by a sleeve 53 held in position thereon by abutting against a shoulder 51^a and a hand 25 operated screw threaded locking member 54 threaded on the upper extremity of the tubular member 51. Secured by screw threading or otherwise to the lower extremity of the tubular device 51, 53 is a member 55 hav- 30 ing two depending branches spaced apart a sufficient distance to engage the opposite inner surfaces of the parallel bars 45, 46. Between the branches of the part 55 is a block 56 held in position by the pivot pin 47 and having one end of a threaded rod 57 journaled in a non-threaded opening therein and held against longitudinal movement with relation to the block 56 by a collar 57^a 40 secured thereon, there being a hand wheel 45 57^b on the outer exposed end of the rod 57 for rotating it. The threaded rod 57 engages a co-operating threaded block 58 slid- 50 ingly mounted on spaced bars 45, 46 and being secured to one extremity of a rela- tively powerful coiled spring 59 secured by the eye 60 at its other extremity to the auxiliary table top 24. The function of the spring 59 is to resiliently sustain the auxiliary table top 24. A bar 61 is 55 pivotally connected at 62 to a bracket 63 secured to the underside of the auxiliary table top 24, and at its lower extremity passes through an elongated slot formed by the keeper bar 64 spaced apart and secured 60 to the bar 46 by the pivot bolt 47 and the spacing member or washer 65. As a means for adjustably securing the keeper bar 64 into locking relation, the other end of the keeper bar 64 is adapted to take a threaded 65 bolt 66 secured to the bar 46 and having a winged nut 67 by which a clamping action between the parts 46 and 64 may be exerted to hold the bar 61 and consequently the parts connected therewith and controlling the auxiliary table section 24 in their ad- 70 justed positions.

Details of the construction of the intermediate table section 23 and its controlling devices will now be described.

In the top plan view of the various sec- 75 tions of the table top shown in Fig. 2 the construction of the intermediate table section 23 and the co-operating main and auxiliary table sections is clearly shown, and from which it will be seen that the inside 80 end of the main table section is cut in the form of a semi-circumference to accommodate the convexly curved intermediate section 23 which latter is in the form of a half circle, being hinged along its diameter to the 85 table top section 24, there being three of these hinges as indicated by the reference character 70 shown on Fig. 7. This hinge connection between the intermediate semi-circular leaf 23 and the auxiliary section 24 90 will obviously permit relative movement between the two sections along the axis of the hinge connections, first, to permit the auxiliary section to be elevated or depressed independently of the intermediate section 95 and second to permit raising and lowering of the intermediate section 23 within cer- 100 tain limits on hinge connection 70. Inasmuch as intermediate table section 23 is thus positively connected with the auxiliary sec- 105 tion 24 and will move therewith when the auxiliary section is oscillated or vibrated on the axis pin 40 in a horizontal plane the circular cut in the end of the main table top 22 and the corresponding circular shape 110 given to the intermediate section 23 are 105 essential to permit freedom of movement as described.

Under some conditions it is found that to allow the intermediate table section 23 110 to remain in the elevated position, that is in the plane of the table sections 22 and 24, will result in contact of the section 23 in an objectionable manner with the body of the patient, and tend to chafe the same. 115 For this reason I provide means for lower- 120 ing or depressing the intermediate section 23 on the axis of its hinged connections 70 with the auxiliary table section, when it is desired to operate the auxiliary table sec- 125 tion with the intermediate section thus de- 130 pressed. The bracket 42 secured to the shaft 40 and supporting the hinged auxiliary section 24 is provided with one or more branches or projections as indicated by the center projection 42^a and the end projections 42^b. These projections are beveled along their upper edges to permit the intermediate table section 23 to be dropped below the normal plane of the said section 23 and the 130

normal plane of sections 22 and 24. This dropping movement of the section 23 is a swinging movement on the hinges 70 and is under the control of the operator at the side 5 of the table top through a crank member the shaft of which is indicated by the reference character 75, the same being journaled on the under sides of the extensions 42^a and 42^b. An adjusting handle or arm is formed 10 on the shaft 75 as indicated by the reference character 76, and at its opposite extremity the shaft 75 is provided with a crank arm or angular portion 77 terminating in a crank pin indicated by the reference character 15 78 (see Figs. 7 and 11). The crank pin 78 is in an engagement with the spaced plates 79 and 80, (Fig. 8) the latter of which is secured to slide loosely on pins or screws 81, 82, which pass through openings in said 20 plates 79 and 80 and are secured into the body of the intermediate leaf 23 and on the underside thereof. The plate 79 is preferably provided with a depending flange along one edge furnishing a sort of a housing 25 for the crank pin 78, as indicated by 79^a, and springs 84 hold plate 80 against the crank pin.

In Fig. 1 showing a side elevation view 30 of my complete table upholstering or padding is indicated by dotted lines as being secured to the upper side of the main auxiliary and intermediate table sections. Any sort of material of sufficient resiliency to furnish protection to the body of the patient 35 may be employed, and forms no part of the invention herein.

Generally speaking the operation of my improved table is about as follows:

The patient is placed in position lying 40 flat upon the flat table top formed by the main, auxiliary and intermediate sections with that portion of the body or frame of the patient into which it is desired that flexing or moving of the joints shall be secured. 45 A portion of the body of the patient may for an example be strapped or otherwise secured to the main table section 22, and by swinging the auxiliary and intermediate table sections on the vertical axis 40 holding 50 another portion of the patient's body more or less securely on these table sections would result in a flexing or moving of one portion of the patient's frame or skeleton in relation to the parts secured to the main 55 table section 22. When it is desired to have the table sections 22, 23, and 24 all lying in the same plane and rigidly held in such plane, this may be accomplished by manipulating the operating handle 76 which will 60 elevate and retain or lock the intermediate table section 23 in its elevated or normal position, shown in Fig. 1. At the same time the operator may prevent any vibrating or swinging movement in a horizontal plane

on the axis pin 40 of the auxiliary and intermediate table sections 24 and 23 respectively by operating the hand wheel of the screw 83 (see Figs. 1 and 6). The screw 83 which is threaded in the depending branch 12^b by contact at its inner extremity 70 with the shaft 40 will thus lock the shaft 40 and table sections 23 and 24 against rotation in a horizontal plane. When hand nut 67 is tightened clamping the bar 61 rigidly to the parallel bars 45, 46, it will be 75 apparent that the auxiliary section 24 will be rigidly locked to the vertical shaft 40 against movement in vertical planes.

When the binding screw 83 is released so that it does not contact with the vertical 80 shaft 40 it will be obvious that the auxiliary and intermediate table sections may be swung in horizontal planes from side to side on the axis shaft 40 and that the operator may by manipulating rod 57 shift the spring 85 block 58 backward and forward between the parallel bars 45, 46 thus varying the leverage to be exerted upon the spring 59 when the auxiliary table top is depressed, on its hinged connections at its outer or free end. 90 This adjustment obviously will enable the operator to vary the carrying capacity of the auxiliary table within certain limits while the adjustment already referred to 95 provided in the compound connecting rod details of which is shown most clearly in Figs. 1, 6, 9 and 10, may be employed to secure a further range of adjustment in the elastic carrying capacity of the auxiliary table section.

For the purpose of setting up resistance to lateral movement of the auxiliary or swinging table section 24 and the intermediate section 23 hingedly connected thereto, I prefer to provide elastic means in the form of a tension spring 41^b (see Figs. 1, 7 and 12). This tension spring is secured at one end to a projection on the collar 41 rigidly secured to the vertical shaft 40 carrying both table sections 23 and 24 and the other end of the spring is adjustably secured by means of a threaded eye-bolt 41^c to a clip 41^a fixed to the frame member 12^c. This construction, it will be seen, will cause the tension of spring 41^b to be exerted whenever the vertical shaft 40 is rotated, and will tend to hold the table sections 24 and 23 in the normal extended positions shown for example in the top plan view Fig. 2.

In addition to the binding screw 83 which 120 may be used to lock the vertical shaft 40 against rotation, I provide a locking device shown in Fig. 2 which may be used also for locking the auxiliary and the intermediate table sections 23 and 24 against horizontal 125 rotation on the axis 40, or, in other words, may lock the intermediate section 23 to the main table top section 22 when the inter-

mediate section 23 is in its elevated position flush with the plane of the sections 22 and 24.

This device is shown in Fig. 2, and consists of plunger or pin 100, slidably carried by clips 102 on the under side of the table section 22, and controlled by a spring 101 adapted to force it normally toward the intermediate section 23 to engage in an opening between the clip 103 and the intermediate section 23, thus effectively locking the sections 22 and 23 together.

Should the intermediate table section 23 tend to rub or abrade the body of the patient or otherwise annoy, the operator, by manipulating the hand lever 76 in the manner already described, may allow the intermediate table section 23 to drop downwardly on its hinges, as indicated in Fig. 12, in which position it will be throughout most of its surface, considerably below the auxiliary and main table sections.

A stretching movement is obtained by securing different portions of the patient's body to the intermediate and auxiliary table sections and to the main table section 22 and then operating the hand crank 28^a which will cause the main table section to be drawn apart from the intermediate section 23 sliding on the supporting rods 19 and 20 through its connections in the manner already described. If it is desired to give a twisting movement on the longitudinal axis of the table top 22 this may be secured by fastening the patient's body to the intermediate and auxiliary table sections in their stationary positions and releasing the projections 36 on the lever 35 from contact with the bracket member 26, which will permit the main table section 22 to swing on the shaft 28 in the manner already described and subject to the adjustment of set screw 26^a and the adjustable bearing shoe 26^b which coöperates with the adjusting rod 28.

From the above description it will be seen that the construction of my improved table is such that the table is adapted to the securing of a great variety of swinging and twisting movements between various portions of the human body when placed thereon in various relations thereto, and the invention is found admirably adapted, as already stated, for the use of osteopaths and other persons practising movement cures of the various kinds in the different schools of medicine and surgery.

While I have shown the invention and specifically described it in the embodiment of the invention preferred by me, I do not desire to be limited to the exact details shown, because it is apparent that persons skilled in this art may resort to various modifications without departing from the purpose and spirit of my invention.

In order that the invention might be understood the details of the preferred embodiment of my invention have been shown and described, but it is not desired to be limited to the details referred to, for it will be apparent that persons skilled in the art may employ variations in the arrangements of the structure without departing from the purpose and spirit of the invention.

I claim:

1. The combination in a table of the described character, of a main table section having one end cut away on a reverse curve on the arc of a circle of a diameter of substantially the width of the said main table section, an auxiliary table section, an intermediate table section of substantially semi-circular form and coöperating with the cut away end of the main table section and being hinged on the side constituting its diameter to the auxiliary table section whereby said intermediate section may be moved on its hinge out of the plane of the main and auxiliary table sections, unitary means for supporting said main, auxiliary and intermediate table sections at different elevations, means for articulating said auxiliary table section in relation to the main table section and to the supporting means whereby the said auxiliary table section has a limited universal movement in relation to the main table top section and the supporting means, and resilient means tending to sustain said auxiliary and intermediate table sections in normal positions, said resilient means resisting the movement of both said auxiliary and intermediate table sections out of normal on the vertical axis but resisting the movement of the auxiliary table section only when said auxiliary table section is moved on its horizontal axis.

2. In a treating table of the described character, the combination with a main table section, of supporting means comprising a base, a standard adjustably secured to the base for carrying the main table section, means for varying the relations of the standard and the base to secure variations in height of the table top including the main table section, a bracket carried by the standard, means for supporting the main table section from said bracket permitting a longitudinal adjustment of the main table section in relation to the bracket and permitting a canting or rocking adjustment of the main table section on an axis approximately parallel with the longitudinal axis of the main table top, an auxiliary table section secured to the said bracket and coöperating with the main table section, said auxiliary table section being resiliently supported and being adapted to have universal movement in relation to said bracket and main table section, the end of the main table section adjacent

the auxiliary table section being reversely curved, and a correspondingly curved intermediate table section coöperating with the said curved end of the main table section 5 and being hingedly connected to the auxiliary section to have movement out of the plane of the latter.

3. The combination in a treating table, of a main table section and supporting means therefor, means for permitting a rocking or 10 canting movement of the main table section on a horizontal axis, an auxiliary table section capable of lateral or side to side movement in a horizontal plane relative to said main table section, one end of the main table section being reversely curved adjacent the auxiliary table section, and an intermediate table section hingedly connected to said auxiliary table section, being movable therewith 15 during lateral or side to side movements of said auxiliary table section and lying adjacent and coöperating to close the gap in the reversely curved end of the main table section. 20

4. In a treating table of the described character, the combination with a main table section, of supporting means comprising a base, a standard adjustably secured to the base, means for varying the relations of the 25 standard and the base to secure variations in the height of the table top, including the main table section, a bracket carried by the standard, means for supporting the main table section from the said bracket permitting a longitudinal adjustment of the main 30 table section in relation to the bracket, and permitting a canting or rocking adjustment of the main table section on an axis approximately parallel with the longitudinal direction of the main table top, and 35 an auxiliary table section secured to the said bracket and coöperating with the main table section, said auxiliary table section being resiliently supported and being adapted to 40 have universal movement in relation to the said bracket and main table section. 45

5. The combination in a table of the class specified, of a main table section or top having supporting means, means for permitting 50 a longitudinal adjustment of said main table section or top, an auxiliary table section supported by and movably associated with the said supporting means of the main table section, and means for resiliently supporting 55 the auxiliary table section with respect to relative movements in vertical planes.

6. In a treating table, the combination of a main table section or top and supporting means therefor, means for adjusting said 60 main table section or top longitudinally in relation to the said supporting means, an auxiliary table section or top attached to and supported by means on the main table support, said last mentioned means being 65 adapted to permit lateral movement of the

auxiliary table section in relation to the main table section.

7. The combination in a treating table of a main table section and supporting means therefor, means for permitting a rocking or 70 canting movement of the main table section from side to side, and an auxiliary table section capable of lateral or side to side movement in a horizontal plane relative to said main table section. 75

8. The combination in a treating table of the described character having a main table section or top and supporting means therefor, of means for permitting the main table section or top to be inclined at an angle 80 laterally and on the longitudinal axis of said table top, an auxiliary table section attached to and movably associated with the supporting means of said main table section, said auxiliary table section being capable of 85 lateral movement in the plane of the main table section or top.

9. The combination in a treating table of the described character, of a main table section or top and supporting means therefor, 90 of means for permitting the longitudinal adjustment of said main table section in relation to the supporting means, an auxiliary table section movably associated with said supporting means for the main table section 95 or top, means for permitting a lateral movement of said auxiliary table section, and means for setting up resilient resistance to the said lateral movement of the auxiliary table section. 100

10. In a treating table of the described character, the combination with a main table section or top and supporting means therefor, of means for adjusting said main table section or top longitudinally in relation to 105 its said supporting means, an auxiliary table section or top, means for permitting a lateral pivotal movement of said auxiliary table section or top relative to the main table section, and means for vertically adjusting both said main table section or top and the said auxiliary table section or top synchronously. 110

11. The combination in an osteopathic table, of a main table-section and supporting 115 means therefor, an auxiliary table-section pivotedly mounted to swing on a vertical axis, an intermediate leaf or section interposed between the said main table-section and auxiliary table-section and hinged to the latter, and being adapted to be depressed at its free end below the plane of the table-top, means for adjusting the said intermediate hinged table-section in and below the plane of the main and auxiliary table-sections, and means under control of the operator for rigidly locking said intermediate and auxiliary sections against lateral swinging movement on their vertical axis in relation to the main table-section. 125 130

12. The combination in an osteopathic table, of a main table-section and supporting means therefor, an auxiliary table-section pivotally mounted to swing on a vertical axis, an intermediate leaf or section interposed between said main table-section and said auxiliary table-section and being hinged to the latter and adapted to be depressed at its free end below the plane of the 5 table-top, means for adjusting said intermediate hinged table-section in and below the plane of the main and auxiliary table-sections, means under the control of the operator for rigidly locking said intermediate and auxiliary sections against lateral swinging movement on their vertical axis in relation to the main table-section, and means for setting up resistance to lateral swinging movements of the said auxiliary table-section 10 on its said vertical axis.
13. The combination in an osteopathic table, of a main table-section and supporting means therefor, said main table section being provided with a curved or recessed 15 end at one extremity thereof, an auxiliary table-section pivotally mounted to swing on a vertical axis, an intermediate leaf or section interposed between said main table section and said auxiliary table-section and being hinged to the latter and adapted to be depressed at its free end below the plane of the 20 table-top, said intermediate leaf or section being curved to conform with the adjacent curved end of the main table-section, means for adjusting the said intermediate hinged table-section in and below the plane of the main and auxiliary table-sections, and means under the control of the operator for rigidly locking said intermediate and auxiliary 25 sections against lateral swinging movement on their vertical axis in relation to the main table-section.
14. The combination in an osteopathic table, of a two-part adjustable pedestal, 30 means for locking the two parts of the said pedestal together, a table supporting frame secured to one of the relatively movable parts of the pedestal and comprising a body portion and a vertically arranged tubular portion carried thereby adjacent the pedestal, a pivot rod rotatably journaled in said tubular portion, a table-leaf hingedly connected with said pivot rod and carried thereby, a pair of approximately parallel branches carried by the said frame member, a main table-section slidably mounted on said parallel branches and supported thereby, and means for adjusting said main table top in relation to said parallel supporting branches. 35
15. The combination in an osteopathic table, of a main table-section and supporting means therefor, an auxiliary table-section pivotally mounted to swing on a vertical axis and being carried by the supporting means for the main table-section, an intermediate leaf or section interposed between the said main table section and auxiliary table section and hinged to the latter, and being adapted to be depressed at its free 40 end below the plane of the table-top, and means for adjusting the said intermediate hinged table-section in and below the plane of the main and auxiliary table-sections, said means comprising a crank-rod, one part 45 thereof being journaled in the intermediate leaf and another part of the said crank portion being operatively connected with the said hinged intermediate leaf. 50

In testimony whereof I have signed my name to this specification, in the presence of two subscribing witnesses, on this 15th day of September A. D. 1914.

JOHN V. McMANIS.
